CLAIM

The ornamental design for a makeup brush with flower-shaped brush head, as shown and described.

DESCRIPTION

FIG. 1 is a front elevation view of a makeup brush with flower-shaped brush head, showing my new design;

FIG. 2 is a back elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlargement view of the portion of FIG. 1 enclosed within Circle 9; and,

FIG. 10 is an enlargement view of the portion of FIG. 7 enclosed within Circle 10.

The enlargement indicia rendered in broken lines in FIGS. 1 and 7 illustrate the bounds of the enlargement views (FIGS. 9 and 10) and form no part of the claimed design.
